UNITED STATES PATENT OFFICE.

ULYSSES G. SWEENEY, OF CUTLER, CALIFORNIA.

DOOR-SUPPORT.

1,264,578.

Specification of Letters Patent. Patented Apr. 30, 1918.

Application filed June 18, 1917. Serial No. 175,435.

To all whom it may concern:

Be it known that I, ULYSSES G. SWEENEY, a citizen of the United States, residing at Cutler, in the county of Tulare and State of California, have invented a new and useful Door-Support, of which the following is a specification.

By way of explanation it may be stated that the framework of a door, and particularly the framework of a screen door not infrequently sags at its outer edge, and as a consequence, there exists an undesirable opening at the top of the door.

In view of the foregoing, one object of the present invention is to provide novel means for connecting the constituent members of a door frame, so that the door will not sag.

Another object of the invention is to provide novel means for assembling a flexible element with the constituent members of a door frame, and to provide means for tightening the flexible element to accomplish the end above mentioned.

It is within the province of the disclosure to improve generally and to enhance the utility of devices of that type to which the present invention appertains.

With the above and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed, without departing from the spirit of the invention.

In the accompanying drawings:

Figure 1 shows in section, a part of a door frame whereunto the device forming the subject matter of this application has been applied;

Fig. 2 is a section on the line 2—2 of Fig. 1;

Fig. 3 is an elevation of the device shown in Fig. 1;

Fig. 4 is a section showing a modification.

As shown in Fig. 2, there appears a door 1 including a front stile 2, a back stile 3 and a bottom rail 4, the latter having tenons 5 received in mortises 6 in the stiles 2 and 3. In the forward edge of the front stile 2 there is fashioned a groove 7 communicating with a groove 8 in the bottom rail 4, the groove 8 opening into a groove 9 in the outer edge of the back stile 3 of the door. In

the back stile 3 there is formed a recess 10 located at the base of the groove 9 and communicating with said groove. Rollers 11 are journaled on the stiles 2 and 3 adjacent the lower corners of the door. Mounted in the groove 9 at the ends of the recess 10 are U-shaped supports 12 which may be made of metal. A securing device such as a screw 14 is mounted in the stile 2 at the base of the groove 7 and near to the upper end of the groove. A securing device 15, which may be a screw, is mounted in the stile 3, in the groove 9, and adjacent the upper end of the groove. The numeral 16 denotes a U-shaped flexible element which may be a piece of wire, comprising parallel arms A and a bend B. The flexible element 16 is looped at its bend B over the securing device 14 and is extended, along the grooves 7, 8 and 9, across the rollers 11, and through the supports 12, the ends of the flexible element being attached to the securing device 15. A U-shaped saddle 17, which may be made of metal, is inverted over the flexible element 16 opposite to the seat 10. A tightening device 18, which may be a screw, passes through the saddle 17 and engages the stile 3 at the base of the seat 10.

In practical operation, by advancing the screw 18 into the stile 3, the saddle 17 will be advanced with respect to the recess 10, the flexible element 16 will be bent transversely, adjacent the seat 10, the flexible element traveling over the rollers 11, and the stiles 2 and 3 being held assembled with the bottom rail 4, in such a way as to prevent a sagging of the frame. It is to be observed that, as shown at 19, the ends of the tenons 5 are cut back, so that they will be out of the way of the flexible element 16 and will not prevent a proper tightening thereof. As in Fig. 4 of the drawings, a modified form of the invention has been shown. In the said figure, there appears a door 20 including a front stile 21, a bottom rail 23, and a top rail 22, the rails having tenons 24 entering mortises in the stile 21, the tenons 24 being cut back at their ends, as and for the purposes hereinbefore specified. In its outer edge, the front stile 21 has a longitudinal groove 26, and in the said stile, at the base of the groove 26 there is formed a depressed seat 27. The groove 26 communicates with the groove 28 in the upper edge of the top rail 22, and communicates, also, with the groove 29 formed

in the lower edge of the bottom stile 23. A securing device 30 is mounted in the top rail 22 within the contour of the groove 28, and a securing device 31 is mounted in the 5 bottom rail 23 within the contour of the groove 29. The numeral 32 denotes a flexible element looped around the securing device 31 and having its ends connected with the securing device 30, the flexible element, 10 which preferably is a piece of wire, passing along the grooves 29, 27 and 28, and being engaged around rollers 33 located in the groove 27 and journaled on the stile 21 adjacent the forward corners of the door. 15 Mounted in the groove 26 at the ends of the seat 27 are supports 34 of the kind hereinbefore described. A U-shaped saddle 35 is inverted over the intermediate portion of the flexible element 32, and a tightening device, such as a screw 36, passes through the saddle 35 and enters the stile 31 at the base 20 of the seat 27, it being possible, by advancing the tightening device 36 and consequently the saddle 35, to flex the member 32 intermediate its ends, to secure a tightening 25 thereof.

For convenience in claiming the invention, the bottom rail 4 of Fig. 1 may be denominated an intermediate frame member, the 30 stiles 2 and 3 being designated as terminal members. In a similar way, the stile 21 of Fig. 4 constitutes an intermediate member, whereas the rails 22 and 23 form the terminal members for the frame.

35 Although the structure shown in Fig. 1 has been described as being mounted on the bottom of a door frame, it will be obvious that the structure shown in the said figure may be placed at the top of a door, or, if 40 desired, the structure shown in Fig. 1 may be used both at the top and at the bottom of the door.

Copies of this patent may be obtained for five cents each, by addressing the "Commissioner of Patents, Washington, D. C."

Having thus described the invention, what is claimed is:—

1. The combination with the intermediate 45 and terminal frame members of a door, of securing devices carried by the terminal members; a U-shaped flexible element extended along the edges of said members and comprising a bend and approximately parallel arms, the bend being mounted upon one securing device, and the ends of the arms being attached to the other securing device; and a tightening mechanism mounted in one of said members between the arms and having means for engaging both arms, said member having a recess into which the tightening mechanism may be advanced and into which the arms may be flexed.

2. The combination with intermediate and 60 terminal door members having edge grooves, of securing devices carried by the terminal members and located in the grooves; a U-shaped flexible element in the grooves and comprising a bend and arms, the bend being 65 engaged around one securing device, and the terminals of the arms being attached to the other securing device; a U-shaped saddle receiving the arms to permit a separation 70 thereof, and bearing upon the arms, the saddle being received in the groove of one member; and a screw passing through the saddle and engaging said member, the said member being provided, at the base of its groove, 75 with a recess to which the saddle may be advanced, the screw extending between the arms.

In testimony that I claim the foregoing as my own, I have hereto affixed my signature in the presence of two witnesses.

ULYSSES G. SWEENEY.
